UNITED STATES PATENT OFFICE

WILLIAM J. O'NEILL, OF RIVER FOREST, ILLINOIS, ASSIGNOR TO MERCIL PLATING EQUIPMENT COMPANY, OF CHICAGO, ILLINOIS, A CORPORATION OF ILLINOIS

CONVEYING MECHANISM

Application filed June 11, 1930. Serial No. 460,365.

My invention relates to conveying mechanism of the class employing motor driven reels and load supporting cables adapted to be wound upon the reels and supporting means for the reels permitting the reels to be shifted to various positions to suit the locations of the loads to be lifted, transported and lowered thereby. The reel of such an equipment includes an adjusting arm suitably assembled therewith and accessible remotely from the reel for shifting it.

My invention resides, generally speaking, in the provision of controlling means for causing such a reel to be turned in either direction by the motor that is employed to operate it and means accompanying this means and inclusive of a controlling member assembled with the aforesaid arm and also accessible remotely from said reel for manual operation. The motor is preferably an electric motor which, in accordance with my invention, is provided with a switch controlling the motor circuit in a manner to change the direction of the motor to wind or unwind the cable. This switch is also desirably assembled with the reel to travel therewith and the motor, also, is desirably assembled with the reel to also travel therewith. The supporting means for the reel and motor is preferably inclusive of a track and a truck traveling upon the track and carrying the reel and motor. Automatically operating means are desirably also employed for placing the motor in open circuit when the switch is released from manual control.

I will explain my invention more fully by reference to the accompanying drawings in which Fig. 1 is a view in front elevation taken crosswise of the track, which is shown in section, some parts being broken away and shown in section; Fig. 2 is a side elevation of the structure shown in Fig. 1; Fig. 3 is a sectional view on line 3-3 of Fig. 2, on a larger scale; Fig. 4 is a sectional view on line 4-4 of Fig. 3; and Fig. 5 is a diagram illustrating a preferred circuit arrangement.

A track 1, preferably of I-beam construction, is arranged along the course of travel of the load supporting cable 2. A truck 3 is provided with wheels 4 which ride upon

the bottom flanges of the track rail, as indicated most clearly in Fig. 1. A housing 5 is carried by and depends from the truck. A casing 6 of an electric motor 7 is secured to this housing. A reel 8 is carried by and journaled within the housing together with suitable speed reducing gearing 9 through which the motor operates the reel. The cable 2 has one end preferably secured to the housing 5, as indicated in Fig. 1, and the other end attached to the reel whereby the cable may be wound and unwound. Where one end of the cable is anchored as illustrated a sheave 10 is disposed in the shifting bight thereof. A load engaging hook 11 is provided with a stirrup 12 which is journaled upon the sheave shaft.

An adjusting arm composed of angularly related tubular sections 13-14 rigidly coupled by an elbow 15 is secured, by its section 13, to the angular bracket 16 which is bolted to the housing 5, the arm section 13 being seated within the angle of the bracket. The arm section 13 is horizontal and the arm section 14 is vertical and depends a sufficient distance to make it accessible. When the motor and reel are to be shifted the lower end of the arm section 14 is grasped and pulled or pushed upon to move the motor and reel on the track 1 in the direction desired.

A three phase alternating current motor is desirably employed in which case the circuit arrangement illustrated in Fig. 5 is preferred. In this arrangement the three phase generator 17 is provided with terminal contact brushes 18, 19 and 20. The three phase motor 7 is provided with terminal brushes 21, 22 and 23. The switching mechanism for governing the motor circuit to cause the motor to turn in one direction or the other to correspondingly turn the reel and correspondingly lift or lower the load supporting hook 11 is desirably provided upon a square operating shaft 24. This shaft carries three groups of contacts, one group containing four contacts 25 that are spaced ninety degrees apart and are provided upon and electrically connected with and by metallic spokes 26 having a common metallic hub 27 which is fixed upon, but insulated from the shaft 24.

A second group includes three contacts 28 arranged upon a half circle and also spaced apart ninety degrees, these contacts having an electrical and mechanical arrangement and 5 an assembly with the shaft 24 similar to the contacts 25. The remaining group includes three contacts 29 also arranged upon a half circle and also spaced apart ninety degrees, these contacts having an electrical and mechanical arrangement and an assembly with the shaft 24 similar to the contacts of the other groups. One of the contacts 28 has an extension 28' extending along the shaft to be engageable with a contiguous contact 23. 10 One of the contacts 29 also has an extension 29' extending along the shaft to be engageable with a contiguous contact 22. The shaft 24 is provided with means to be described, whereby it may be turned in one direction 15 to close the motor circuit in one way to cause the motor to be turned in one direction and whereby said shaft may be turned in an opposite direction to close the motor circuit in an alternative way to reverse the direction 20 of rotation of the motor. Automatic means are provided for restoring said shaft to a normal position in which the motor circuit is open. The automatic means illustrated is desirably inclusive of an arm 30 anchored 25 upon one end of the shaft 24, a pin 31 carried upon this arm and extending along the shaft, a second pin 32 stationarily mounted upon the housing and also extending along the aforesaid shaft, unmounted end portions of 30 these pins being in lapping relation, and a floating coil spring 33 wound about the shaft 24 and embracing said pins between its ends, as illustrated in Figs. 1, 3 and 5. When the shaft 24 is turned in either direction from normal, one or the other of the ends of said 35 spring is moved away from the pin 32 by the pin 31, the shaft being obviously restored to its normal position when circuit closing operation thereof ceases. The means for turning 40 the aforesaid shaft in one direction or the other to cause rotation of the motor in one direction or the other is desirably inclusive of an arm 34 which springs from the arm 30, an arm 35 upon an operating shaft section 36, a link 37 uniting the arms 34 and 35, a bevel gear 38 upon the shaft section 36, a bevel gear 39 meshing with the bevel gear 38 on another operating shaft section 40. The operating shaft section 36 desirably 45 passes through the bore of the tubular arm section 13. The operating shaft section 40 desirably passes through the bore of the tubular arm section 14. The contiguous ends of the operating shaft sections 13 and 14 are 50 desirably journaled in the elbow 15. The operating shaft section 40 desirably projects downwardly through the tubular arm section 14 and terminates in a handle 41, whereby it may be turned in either direction to correspondingly turn the operating shaft sec- 55

tion 36 to cause the switch shaft 24 to be turned in one direction or the other to close the motor switch in one manner or the other to cause the motor to turn in the selected direction. The lower part of the arm section 70 14 and the handle 41 are conveniently positioned remotely from the motor and reel, whereby such motor and reel may readily be shifted to shift the location of the load supporting hook as desired, it being unnecessary for the operator to shift his own location in order to control the direction of rotation of the motor and reel after having shifted such motor and reel suitably to the location 75 of the load to be lifted and the place where the load is to be deposited. After the load has been lifted or lowered, the handle is released whereupon the spring 33 places the motor in open circuit. A skillful operator might continue to hold the handle in circuit closing position during the time or during a part of the time that the load is being shifted, the handle to be released when the load has been sufficiently lifted or lowered in order that the motor may then be stopped. 80 All of these advantages are procurable by the structure of my invention which is also a simplification of the controlling mechanism hitherto employed.

Changes may be made without departing 85 from the invention.

Having thus described my invention, I claim:

In a conveying mechanism, including a wheeled truck having a motor operated hoisting reel mounted thereon, a housing for the reel, an adjusting arm extending a substantial distance from the reel and comprising a rigid horizontal tubular section having its inner end secured to the reel housing and its outer end extending laterally a substantial distance of the line of travel of the reel, a hollow elbow rigidly secured to the outer end of the horizontal section, a depending hollow vertical section rigidly secured at its upper end to the elbow, rotatable operating shafts in said hollow sections connected by bevel gearing in the elbow, a switch operating shaft parallel to said horizontal section and carrying a switch at the inner end of said sections operable by rotation of the shafts, link united parallel arms connecting said shafts and said switch operating shaft, a rotatable handle at the lower end of the depending section for rotating the shafts to close the switch, and automatic means for rotating the shafts to open the switch upon release of the handle.

In witness whereof, I hereunto subscribe my name.

WILLIAM J. O'NEILL.
